UNITED STATES PATENT OFFICE

151,605

DESIGN FOR A DESK LAMP

Tom Dolan, Berwyn, Ill., assignor to Standard Business Machines Company, Chicago, Ill., a corporation of Illinois

Application January 15, 1947, Serial No. 136,155

Term of patent 7 years

(Cl. D48—20)

To all whom it may concern:

Be it known that I, Tom Dolan, a citizen of the United States, residing at 6804 Windsor Avenue, Berwyn, in the county of Cook and State of Illinois, have invented a new, original, and ornamental Design for Desk Lamp, of which the following is a specification, reference being had to the accompanying drawings, forming part thereof.

Figure 1 is a perspective view of a desk lamp, showing my new design;

Figure 2 is a top view of the desk lamp shown in Figure 1;

Figure 3 is an end view of the desk lamp shown in Figure 1, the arms supporting the reflector being shown in extended position; and

Figure 4 is a rear view of the desk lamp shown in Figure 1, the arms supporting the reflector being shown extended to a position different from that in Figure 3.

The desk lamp of my design is characterized by the base member.

I claim:

The ornamental design for a desk lamp, as shown and described.

TOM DOLAN.
